UNITED STATES PATENT OFFICE.

FRANZ LÖSEL, OF BRUNN, CZECHOSLOVAKIA.

TURBINE LOCOMOTIVE.

Application filed August 17, 1923, Serial No. 657,843, and in Germany December 27, 1922.

The subject of the present invention is a turbo-electric locomotive and the object generally of the invention is a locomotive which may be driven either directly by the turbine, 5 by electrical energy received from a power transmission line, or by both the turbine and the electrical energy received from the line, and moreover a locomotive in which both the braking energy of the locomotive or train 10 and the surplus power of the turbine may be returned to the line.

Locomotives built in accordance with the invention are particularly suitable for operation on roads which are only partly electrified and which possess widely varying gradients, since such a turbine can operate with equal facility and efficiency on both the electrified and on the non-electrified parts of the line. While on the electrified part of the 20 line the excess power produced by the turbine can be given up to the net work and a heavy demand upon the locomotive can be met by a withdrawal of the current from the net work. An automatic balance of the 25 greatly varying loads is thus obtained and particularly during alternating up hill and down hill runs, the excess energy being supplemented on the down hill runs by the braking energy of the train. Other advantages are the ease of regulating the speed of 30 travel and the stopping and starting of the train. The turbine itself can thus work uninterruptedly with a most favorable and economical load, a smaller consumption of 35 fuel and a more economical operation resulting. Moreover the stopping and starting of the turbine on arrival and while standing at stations, which is so disadvantageous with condensation working, is not necessary, and 40 since speed can be regulated by electrical switches or the like, controlling devices for the turbine itself need only be very simple and in some cases may be omitted. The invention also renders unnecessary the provision 45 on the locomotive of accumulators for storing up electricity.

It is clear that the invention offers advantages for both wholly electrified or partly electrified tracks and particularly for tracks 50 in which the current is obtained from water power which is often insufficient for heavy traffic or during the dry months. By mixed operation on such a track with purely electrical trains and turbine locomotives built in 55 accordance with this invention, this occasional lack of energy can at any time be

supplemented in a simple, inexpensive and economical manner.

One embodiment of the invention is illustrated diagrammatically in the accompanying 60 drawing.

In the embodiment shown the transmission line or net work is indicated at n and the turbine unit by t and a dynamo electrical unit g_1 is indicated as connected with the 65 transmission line n by means of the line conductors l_4 and l_5 and the controlling switch mechanism indicated at S . The turbine t is mechanically coupled to the dynamo unit g_1 by means of a clutch k adapted 70 to be engaged or disengaged by the operation of a hand wheel or the like (omitted for convenience in illustration). In the embodiment shown the dynamo electric unit g_1 functions both as a motor and a generator, as 75 for example being in the form of an asynchronous generator, and when run as a motor, power is transmitted to the locomotive axles by means of toothed gearing (not shown) directly from the generator or motor shaft, the drive being diagrammatically 80 illustrated.

Experience with ships and with already known turbine locomotives shows that such toothed gearing operates quite satisfactorily, 85 and even where large powers are to be transmitted, is sufficiently durable.

The turbine t drives the generator g_1 and the latter drives the driving axles while the current produced by the generator is led 90 through the switch S to the net work n . When uncoupled from the turbine t and connected to the net work n the generator g_1 acts as a motor and drives the axles alone 95 and when coupled to the turbine t it may still act as an electric motor to drive the locomotive when the turbine power is insufficient to assume the whole load. On a down grade a part or all of the braking effort is taken over by the generator and the current 100 thereby produced returned or delivered to the net work n .

Obviously the power might be transmitted to the locomotive axles from the turbine shaft or from both the turbine shaft 105 and the generator shaft; and on non-electrified portions of the track the dynamo electric unit g_1 may be uncoupled and the locomotive driven by the turbine only, the drives from the motor-generator and turbine 110 shafts being diagrammatically illustrated and including respectively the clutches a

and *b*. For convenience in illustration I have shown the motor and generator as combined into a single unit instead of separate motor and generator units and moreover the combined unit is to be preferred from certain considerations.

I claim:

1. In a turbo-electric locomotive, a turbine, a motor-generator adapted to be mechanically coupled with the locomotive, electrical connections leading from said motor-generator to a net work, a switch for controlling said connections and disconnectible means mechanically coupling the turbine to said 15 motor-generator and the locomotive.
2. In a turbo-electric locomotive, an electrically reversible dynamo electric machine adapted to be mechanically coupled with the locomotive and to either generate electrical 20 power as a generator or to receive electrical

power as a motor, means electrically connecting said machine with a transmission line and a steam turbine mechanically coupled with the locomotive and the dynamo electric machine so as to mechanically drive 25 the locomotive and drive the machine as a generator.

3. In a turbo-electric locomotive of the character set forth in claim 2 including disconnectible couplings between the turbine 30 and the locomotive and between the dynamo electric machine and locomotive and a direct connection between the turbine and the dynamo whereby the turbine may drive the dynamo electric machine independently of 35 the locomotive.

In testimony whereof I have signed my name to this specification.

FRANZ LÖSEL.
